UNITED STATES PATENT OFFICE.

MILLER REESE HUTCHISON, OF WEST ORANGE, NEW JERSEY, ASSIGNOR TO MILLER REESE HUTCHISON, INC., A CORPORATION OF NEW JERSEY.

FILING-CABINET WITH LOCKING-COMPARTMENTS.

1,351,423.

Specification of Letters Patent. Patented Aug. 31, 1920.

Application filed June 17, 1919. Serial No. 304,788.

To all whom it may concern:

Be it known that I, MILLER REESE HUTCHISON, a citizen of the United States, and resident of West Orange, in the county of Essex and State of New Jersey, have invented certain new and useful Improvements in Filing-Cabinets with Locking-Compartments, of which the following is a specification.

10 This invention relates to filing racks, fixtures or furniture and with regard to its more specific features, to filing cabinets for phonograph records.

One of the objects of the invention is to provide a device of the above type of compact and simplified construction, which shall be substantially proof against incorrect replacement of articles removed therefrom.

20 Another object is to provide a fixture of the character referred to, which shall effectively and with the requirement of small effort on the part of the custodian, bring about the result of maintaining the articles 25 when not in use, in their appointed places at all times.

Other objects will be in part obvious and in part pointed out hereinafter.

The invention accordingly consists in the 30 features of construction, combinations of elements and arrangement of parts which will be exemplified in the construction hereinafter described and the scope of the application of which will be pointed out in 35 the following claims.

Referring now to the accompanying drawings wherein is shown one of various possible embodiments of the several features of the invention,

40 Figure 1, is a view in longitudinal section taken along the line 1—1 of Fig. 4, and showing a cradle frame and its associated record locked in place.

Fig. 2, is a view similar to Fig. 1, showing the position of the parts when the record is free to be removed.

Fig. 3, is a fragmentary front view of the cabinet with part of the shutter broken away.

50 Fig. 4, is a fragmentary front view of my cabinet.

Fig. 5, is a fragmentary cross sectional view.

Fig. 6, is a sectional view with parts

broken away, taken along the line 6—6 of Fig. 7.

Fig. 7, is a fragmentary front view with parts broken away, of the lower portion of my cabinet, showing the lower edge of the shutter and the keyhole.

Fig. 8, is a perspective view showing the relation of my key and my coupling rod, and

Fig. 9, is a fragmentary sectional view taken along the line 9—9 of Fig. 6.

Similar reference characters refer to similar parts throughout the several views of the drawings.

This invention is an improvement upon that of my copending application Serial No. 301,520, filed June 3rd, 1919.

Referring now to the drawings, I have shown a filing cabinet provided with a base 1, a top 2, a back wall 3, and lateral walls, one of which is shown at 4 fitting into a corresponding groove 53 in the base.

The base has an upwardly extending flange 54, and the top a downwardly extending flange 55, at the front, said flanges being connected at their ends by vertical 80 slats 56, the two flanges and the slats together constituting an open rectangular front border frame, adapted to be closed by a shutter member 10 theretbehind, to be more fully described below. The slats 56 preferably constitute each a part of an angular corner bracing member 11 on the exterior of the cabinet. An internal bracing member 57 is also preferably provided at each of the four vertical edges.

Within the cabinet are provided, referring more particularly to Figs. 3 and 5, a plurality of equally spaced vertical partitions 5 each preferably fitting into corresponding grooves 6, in the base, and 7 in the top, at 95 their lower and upper edges respectively, forming a plurality of compartments C, one between each two adjacent partitions 5, each for lodging a phonograph record. The rear edges of the partitions preferably fit 100 into grooves 9 in an inner rear partition 8.

As above stated, I preferably provide a single shutter 10 for closing the front of the entire cabinet. This shutter is preferably of a flexible type similar to that employed 105 for roll tops of desks, and briefly stated comprises a series of wooden or fiber slats 12, connected each to the adjacent slat by a

narrow metallic staple element 13, extending the length of the slats into corresponding grooves 14 in the rear thereof. The detailed construction of the shutter member is substantially immaterial, as its construction taken by itself and apart from its use, is part of the prior art and not my invention.

The shutter member is preferably formed in a continuous loop and passes over four rollers located substantially at the four vertical edges of the cabinet, two of said rollers being shown at 15 and 16. The shutter thus has a portion adjacent and parallel to each of the four vertical faces of the cabinet, the 15 front portion closing the opening in the front frame, and the rear portion passing between the rear wall 3 and the partition 8. The rollers are preferably provided with axial metallic pins or gudgeons 17, journaled 20 one into the base member 1 and the other into the top member 2.

The shutter includes in its construction, a port plate 18, having a port 19 of substantially the width of compartment C, for permitting insertion and egress of a record, said plate being preferably provided with undercut lateral grooves 20 into which extend adjacent staples 13 of the regular shutter construction above described, thus forming the shutter and port plate into a continuous loop.

To render possible the ready shifting of the shutter so as to place the slot 19 into registry with any of the compartments C, as desired, I preferably secure a loop handle 21 to the plate 18, as shown. I also preferably provide rigid with the plate 18, a metallic indicator pointer 22 for facilitating the finding of the compartment and record desired, 40 by effecting registry with a corresponding numeral or other indication on the base flange 54.

Referring now more particularly to Figs. 1 and 2 in which I have shown an individual record compartment C, it being understood that the description with respect to Figs. 1 and 2 applies to all of the compartments alike, I have shown a disk phonograph record 23 resting upon a substantially crescent shaped cradle frame 24 having an integral ear 58, said frame being pivoted about a rod 25 extending through said ear. Rod 25 extends preferably the width of the cabinet for performing the same function with respect to all of the cradle frames. The cradle frame is preferably provided with a stop member in the form of a toe 25' having preferably a flat edge 26 in contact with the shutter 10 when the frame is in home or retracted position. When the frame is in the position shown in Fig. 1, toe 25' prevents removal of the record, even if the shutter be out of the way.

A latch support 27 is preferably pivoted 65 about a rod 28, said rod extending the width

of the cabinet to perform the same function with respect to similar latch supports in other compartments. The latch supports preferably carry at their free ends a unitary angular latch bar 29 extending the width of 70 the cabinet and passing through arcuate slots 30 one in each partition 5, the latch bar coöperating with a notch 31, in the ear of cradle frame 24 and similarly with a similar notch in each cradle frame. A leaf spring 75 32 preferably urges the latch bar toward co-operation with the notches 31. Although I may provide a support 27 in each compartment for the common latch bar 29, it is of course obvious that this is not essential, and 80 substantially any lesser number may be employed.

Pivoted on the cradle frame 24, as at 33, I provide a counterlock member 34 having preferably a curved portion extending along 85 a part of the crescent shaped cradle as at 34' and fitting into a corresponding depression 36 therein, to limit the width of the assembly of cradle and counterlock. The counterlock member is urged in a counter 90 clockwise direction about pivot 33 by means of a leaf spring 35 contacting it at one end and secured at the other to the cradle frame. A stationary stop member 59 is provided, having a shoulder 37 for co-operation with the innermost edge 38 of the counterlock member under certain conditions described more fully below.

By my construction thus far described, each record is locked within its compartment by means of the cradle frame and the shutter member is free to be moved to register its slot 19 with any record compartment.

In order to release any record, the latch bar 29 should be depressed. For this purpose, I preferably provide key operated means at the center of the base member. This means is best shown in Figs. 6 and 9, and comprises a link 39 connected to the latch bar preferably by means of an eye 40 105 and extending downwardly into an opening 41 in the base. The link preferably has a shoulder 42 adapted to coöperate with a bit 43 on a coupling rod 44, preferably lodged within a cylindrical opening 45 extending 110 from the front toward the back of the base member. The coupling link has a head 46 provided with a transverse slot 47 for co-operation with the end bit 48 of a key 49, adapted to be inserted into a keyhole 50 near 115 the center of the base of the cabinet. The key also has a lateral bit 51 for a purpose appearing more fully in the operation below. Adjacent the head 46 is provided a metallic inner keyhole plate 61, having a keyhole 65. 120

The lower edge of the shutter is preferably serrated as at 52, so that the shutter cannot be shifted when the key is in its slot as is clear from Fig. 7.

Below the keyhole I preferably provide 130

a cavity in the base, lodging a small drawer 62, having preferably a handle 63, and three compartments 64, one for the key 49, one for used and one for unused needles.

In use, the custodian or operator grasps the handle 21 on the shutter and thereby shifts the latter until the indicator pointer 22 is opposite the indication corresponding to the record he wishes to withdraw. When this position is reached, the port 19 will register with the compartment containing the desired record. To remove the record, the key 49 is inserted into keyhole 50, bit 51 entering the slot portion of the keyhole, thus alining bit 48 for entry into slot 47 in the coupling rod 44. When the key reaches the position shown in Fig. 6, it is turned, whereby bit 43 on the coupling rod moves link 39 downwardly by reason of its engagement with shoulder 42, and the link thereupon withdraws the latch bar 29 against the resistance of spring 32 from the notches 31, thus unlocking all of the cradle frames as in Fig. 2. The compartments that are closed by the shutter are inaccessible and the corresponding cradle frames by reason of the contact between their edges 26 and the shutter 10 are not displaced.

As regards the compartment with which the shutter port registers, the release of the latch bar causes the cradle frame to pivot about rod 25 by reason of the movement of the record and the forward portion of said cradle, until the position shown in Fig. 2, is reached. In this position, it is noted that the record 23 projects through the slot 19 as does the toe 25' of the cradle frame which now no longer blocks egress of the record. The record can then be readily removed by hand. When a record relatively smaller than that shown in the drawings is filed in the cabinet, this record will roll down the inclined beam to the toe 25' upon release of the latch bar. Immediately thereafter, spring 35 moves the counterlock member 34 in a counter clockwise direction to bring edge 38 thereof into contact with shoulder 37 on the stop member 59 and to move part 34' upwardly into a space vacated by the removed record. The shutter as is obvious cannot now be shifted until toe 25', which extends through the port is retracted. The counterlock member, however, prevents such retraction until the record or a similarly shaped article is inserted into the compartment to withdraw said member to the position shown in Fig. 2.

It is thus seen that if a record is withdrawn, the shutter cannot conveniently be moved to permit access to any other compartment until the record is re-inserted in place and the cradle frame restored to the home position shown in Fig. 1.

It is further apparent that by reason of the serrations 52, the shutter member can-

not be shifted until the key is withdrawn from the keyhole. The key however referring to Figs. 2 and 6, cannot be withdrawn until the record is inserted to release the counterlock, thus permitting spring 32 to 70 return the latch bar 29 to locking position, the latter step causing rotation of the coupling rod 44 to bring bit 51 of the key, into alinement with the keyhole 65 in plate 61, thus permitting withdrawal of the key. 75 The key being withdrawn and the record again in place, the shutter 10 is again free to be shifted and the operation may be repeated to withdraw any record in the manner above fully described. 80

It is thus seen that by my invention only one record can be removed at a time, removal of such record preventing the shifting of the shutter for access to any other record until the first record is restored and 85 locked in place and the key withdrawn from the keyhole.

My invention thus at small effort on the part of the custodian or operator, effectively prevents confusion of the records 90 and minimizes the likelihood of breakage or scoring.

Although this invention, as in the case of the co-pending application above referred to, has special utility and its preferable application when applied to cabinets for disk phonograph records, it is understood that it may be applied to numerous other purposes. In general, it is useful in any relation where it is desirable to deliver 100 articles one at a time and compel the return of each to its appointed place before another is accessible. 95

It is apparent that I might arrange my compartments horizontally and arrange the 105 shutter to be raised and lowered for registering the port with the desired compartment, but it is to be understood that I prefer to employ the specific arrangements shown and described. 110

It will thus be seen that there is herein described apparatus in which the several features of this invention are embodied and which apparatus in its action attains the various objects of the invention and is well 115 suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not 125 in a limiting sense.

Having thus described my invention, what I claim as new and desire to secure by Letters Patent is:—

1. In a filing cabinet for phonograph 130

- records, in combination, a plurality of compartments each adapted to have a record locked therein, means for simultaneously unlocking a plurality of said records, and means for permitting removal of but one of said unlocked records.
2. In a filing cabinet for phonograph records, in combination, a plurality of compartments each adapted to have a record locked therein, means for simultaneously unlocking all said records, and means for permitting access to any one selected compartment for record removal, while maintaining the remaining compartments inaccessible.
3. In a filing cabinet for phonograph records, in combination, a plurality of compartments, means for opening any selected compartment, while preventing access to the remainder thereof, a retainer in each compartment for locking a record therein, and means for simultaneously releasing all said retainers, thereby allowing only the record in the selected compartment to be removed.
4. In a filing cabinet for phonograph records, in combination, a plurality of compartments, means for opening any selected compartment, while preventing access to the remainder thereof, a plurality of cradle frames, one in each compartment, each said frame being locked to prevent removal of its associated record, and means for simultaneously releasing all said locks, whereby only the record in the selected compartment can be removed.
5. In a filing cabinet for phonograph records, in combination, a plurality of compartments, means for opening any one selected compartment while maintaining the others closed, a plurality of cradle frames, one in each compartment, each said frame being urged to eject its associated record, locking means for retaining each record in place, and means for simultaneously releasing each said locking means, whereby the record in the selected compartment will be ejected, and the other records will remain inaccessible.
6. In a filing cabinet for phonograph records, in combination, a plurality of compartments, a member across the delivery side of all said compartments, and having means adjustable to allow access to any one selected compartment while maintaining the remaining compartments closed, means for locking a record into each compartment, and means for simultaneously releasing all said records whereby only the record corresponding to the position of the adjustable means can be removed.
7. In a filing cabinet for phonograph records, in combination, a plurality of compartments, a shutter member across the delivery side of all said compartments, said member having a port adjustable in position, for registry with any said compartment, means for locking a record into each compartment, and means for simultaneously releasing all said records, whereby only the record aligned with said port can be removed.
8. In a filing cabinet for phonograph records, in combination, a plurality of compartments, an adjustable band member extending across the delivery opening of all said compartments, and having a port adapted to be placed into registry with any of said compartments, means for locking a record into each compartment, and means to prevent further adjustment of said band member, when the record in the open compartment is unlocked.
9. In a filing cabinet for phonograph records, in combination, a plurality of compartments each for retaining a record, an adjustable flexible shutter adapted to close all said compartments, and having a port adapted to be placed into registry with any thereof to permit access thereto, and means automatically projecting from said cabinet into said port, to prevent shifting of said shutter, when the record in the open compartment is free to be removed.
10. In a filing cabinet for phonograph records, in combination, a plurality of compartments, an adjustable flexible shutter adapted to close all said compartments, and having a port adapted to be placed into registry with any thereof to uncover it, a plurality of cradle frames one in each compartment, each adapted to lodge a record, each said frame having an integral stop member, adapted to project into said port, when the corresponding record is free to be removed.
11. In a filing cabinet for phonograph records, in combination, a plurality of compartments each adapted to retain a record, an adjustable flexible shutter adapted to close all said compartments, and having a port adapted to be placed into registry with any thereof to uncover it, means for locking each record into its compartment, and a stop member responsive to unlocking of the record aligned with said port, to automatically project into said port for preventing further adjustment of said shutter.
12. In a filing cabinet for phonograph records, in combination, a plurality of compartments, an adjustable shutter adapted to close all said compartments, and having a port adapted to be placed into registry with any thereof to uncover it, a plurality of cradle frames, one pivoted into each compartment, each adapted to lodge a record and each urged forwardly, means locking each said frame against said forward tendency to dispose a part thereof in the path for removal of the associated record, each frame having an integral stop member ad-

jaçent its forward end, adapted to enter said port, when the alined frame is unlocked for removal of its record.

13. In a filing cabinet for phonograph records, in combination, a plurality of compartments each adapted to retain a record, an adjustable shutter to close all said compartments, and having a port adapted to be placed into registry with any thereof to uncover it, means for locking each record into its compartment, said means being constructed and arranged to urge each record outwardly, said means including a plurality of stop members one interposed between each record and said shutter, and means for simultaneously unlocking all said records.

14. In a filing cabinet for phonograph records, in combination, a plurality of compartments, a plurality of cradle frames, one in each compartment, each cradle frame being adapted to lodge a record, latching means for all said frames, means preventing removal of said records when said frames are latched, and a single means for simultaneously releasing all said latching means.

15. In a filing cabinet for phonograph records, in combination, a plurality of compartments, a plurality of cradle frames one pivoted in each compartment, each for seating a record, means for latching each said frame to block egress of the associated record, and a single key operated means, for simultaneously unlatching all said frames.

16. In a filing cabinet for phonograph records, in combination, a plurality of cradle frames, each for retaining a record, a latch bar extending transversely of said cabinet for latching all said frames into a position to prevent removal of the records, and a key operated means for releasing said latch bar.

17. In a filing cabinet for phonograph records, in combination, a plurality of compartments, a plurality of cradle frames one pivoted in each compartment, each for seating a record, a latch bar extending transversely of said cabinet, a pivot rod therefor, also transverse of said cabinet, said bar being urged for latching coöperation with a notch in each of said frames, and key operated means for releasing said latch bar to permit removal of a record.

18. In a filing cabinet for phonograph records, in combination, a plurality of compartments, each for containing a record, latching means for preventing egress of said records, including a pivoted latch bar extending transversely of said cabinet, a link secured thereto and extending downwardly therefrom, a coupling rod connected to said link and extending toward the front of said cabinet, said rod having means for coöperation with a key, adapted to be inserted into a slot in the front of said cabinet.

19. In a filing cabinet for phonograph

records, in combination, a plurality of compartments, a shutter member across the delivery side of all said compartments, said member having a port adjustable in position, for registry with any said compartment, a latch bar for locking a record into each compartment, and a key operated means for releasing said latch bar to unlock all said records.

20. In a filing cabinet for phonograph records, in combination, a plurality of compartments, a member across the delivery side of all said compartments, and having a port adjustable to allow access to any one selected compartment, while maintaining the remaining compartments closed, a cradle frame in each compartment, means for latching all said frames to block removal of the records, key operated means for unlatching all said records, and means responsive to unlocking of the record alined with said port, to prevent shifting of said first member.

21. In a filing cabinet for phonograph records, in combination, a plurality of compartments, a shutter member across the delivery side of all said compartments, said member having a port adjustable in position for registry with any said compartment, a cradle frame in each compartment, means for latching all said frames to block removal of the records, a stop member adapted automatically to project into said port to prevent shifting of said shutter, while said record alined with said port is removed and means to prevent retraction of said stop member, until said record is restored.

22. In a filing cabinet for phonograph records, in combination, a plurality of compartments, a shutter member across the delivery side of all said compartments, said member having a port adjustable in position, for registry with any said compartment, a cradle frame in each compartment, means for latching all said frames to block removal of the records, key operated means for unlatching all said frames, thereby permitting removal of the record alined with said port, a stop member adapted automatically to project into said port to prevent shifting of said shutter while said record is removed, and means to prevent withdrawal of the key until said record is restored.

23. In a filing cabinet for phonograph records, in combination, a plurality of compartments each for retaining a record, a shutter member across the delivery side of all said compartments, said member having a port adjustable in position, for registry with any said compartment, latching means for retaining the records therein, a key for releasing said latching means, and serrations on said shutter member one of which embraces the shank of said key, to prevent

shifting of said shutter when the key is in the keyhole.

24. In a filing rack, in combination, a cradle frame pivoted therein, and adapted to lodge a record, an integral stop member for said frame, and means for latching said frame to cause said stop member to block egress of said record, said frame being

urged to move said stop member automatically out of the path of said record when 10 said frame is released.

Signed at New York city, in the county of New York, and State of New York this fourteenth day of June, A. D. 1919.

MILLER REESE HUTCHISON.
